RESTAURANT BUILDING

James S. Raymond, 926 Woodford Ave.,
Youngstown, Ohio

Filed Oct. 10, 1963, Ser. No. 76,935

Term of patent 14 years

(Cl. D13—1)

FIGURE 1 is a side view of a restaurant building, showing my new design;

FIGURE 2 is a front view thereof and

FIGURE 3 is a top plan view thereof.

The dominant features of the design reside in the portions shown in full lines. The other side and rear of the back portion of the building now shown are substantially plain except for a conventional brick and stone pattern.

I claim:

The ornamental design for a restaurant building, as shown and described.
